C. L. JENSEN

Des. 165,759

CHRISTIAN FLAG

Filed Dec. 28, 1949

Inventor

Carl Ladin Jensen

UNITED STATES PATENT OFFICE

165,759

CHRISTIAN FLAG

Carl L. Jensen, Telluride, Colo.

Application December 28, 1949, Serial No. 6,862

Term of patent 7 years

(Cl. D29—17)

To all whom it may concern:

Be it known that I, Carl Ledin Jensen, a citizen of the United States, residing at Telluride, in the county of San Miguel and State of Colorado, have invented a new, original, and ornamental Design for a Christian Flag, of which the following is a specification, reference being had to the accompanying drawing, forming part thereof.

The figure is a plan view of a Christian flag, showing my new design.

I claim:

The ornamental design for a Christian flag, as shown.

CARL L. JENSEN.
